(57) CLAIM

The ornamental design for a golf club head, as shown and described.

DESCRIPTION

FIG. 1 is a first perspective view of an embodiment of a golf club head according to the present design;

FIG. 2 is a second perspective view of the embodiment of FIG. 1;

FIG. 3 is a back elevational view of the embodiment of FIG. 1;

FIG. 4 is a front elevational view of the embodiment of FIG. 1;

FIG. 5 is a top-plan view of the embodiment of FIG. 1;

FIG. 6 is a bottom-plan view of the embodiment of FIG. 1;

FIG. 7 is a left-side elevational view of the embodiment of FIG. 1;

FIG. 8 is a right-side elevational view of the embodiment of FIG. 1;

FIG. 9 is a cross-sectional view of the embodiment of FIG. 1, corresponding to section 9 of FIG. 3; and

FIG. 10 is a cross-sectional view of the embodiment of FIG. 1, corresponding to section 10 of FIG. 3; and,

FIG. 11 is a cross-sectional view of the embodiment of FIG. 1, corresponding to section 11 of FIG. 3.

Phantom lining, where utilized, is for illustrative purposes only and forms no part of the claimed design.

The cross-hatched portions of FIGS. 9, 10 and 11 are for illustrative purposes only and the cross-hatched portion of the golf club forms no part of the claimed design.
